UNITED STATES PATENT OFFICE.

ALEXANDER W. COPLAND, OF DETROIT, MICHIGAN

DEPOSITING-MACHINE.

No. 801,511.

Specification of Letters Patent.

Patented Oct. 10, 1905.

Application filed November 7, 1904. Serial No. 231,722.

To all whom it may concern:

Be it known that I, ALEXANDER W. COPLAND, a citizen of the United States, residing at Detroit, in the county of Wayne and State of Michigan, have invented certain new and useful Improvements in Depositing-Machines, of which the following is a specification, reference being had therein to the accompanying drawings.

10 The invention relates to new and useful improvements in depositing-machines; and it consists in the construction particularly of the means for receiving the dough from the hopper and depositing it, and, further, in the construction, arrangement, and combination of the various parts, as more fully hereinafter described, and particularly pointed out in the claims.

15 In the drawings, Figures 1 and 2 are side elevations of opposite sides of my machine. Fig. 3 is a vertical section through the hopper, valve, and discharge-nozzle. Fig. 4 is a similar section showing the segmental piston in a different position. Fig. 5 is a vertical 25 central section on line $\alpha\alpha$ of Fig. 3. Figs. 6 and 7 are perspective views of the piston and abutment-block.

20 A is the framework which supports the operating parts, having a main drive-shaft B, driven from any suitable source of power. C is a tilting table pivoted near one end on the shaft C' and at its other end supported on each side by links D, supported on the levers E, keyed on the shaft E' and operated by a 25 suitable cam on the shaft B, so that the table can be raised and lowered the desired amount. On the table C is a carrier F. This carrier passes over the rollers a and b at opposite ends of the table. The carrier is fed forward 30 by means of the pawl c on the lever d, which is connected by the link e to the upper end of the lever f, which is moved in one direction by the spring f' and in the other direction by a suitable cam on the shaft B, bearing on a 35 roller f'' on the lever f, these parts being no part of my present invention, and I do not deem it necessary to further describe them.

40 G is a hopper provided with a lateral exit-port G' at the bottom. The base H of the hopper is provided with a slot I. In place of the slot I may make a series of separated ports, if desired; but for convenience in cleaning I prefer the single slot. Below the slot or port I is detachably secured a nozzle-plate 45 J, having a slot or a series of discharge-openings h therethrough, and preferably having a

nozzle around each opening, as shown. In the wall K and in the base of the hopper adjacent to the discharge-port G' are formed bearings in which is journaled the cylinder L. 50 This cylinder extends at its ends into the cylindrical extensions i i', formed at the base of the hopper. The extension i' has an enlargement j, into which the cylinder also extends. In this enlargement and secured to 55 the cylinder is the gear k. l is an end plate, having the central extension m projecting into the cylinder. This end plate is bolted or otherwise secured to the enlargement j of the hopper, so as to prevent it from rotation. 60 The projection m is provided with a squared bearing n, in which engages an extension o on the end of the stationary segmental abutment-block o', which extends through the cylinder. At the other end the block is provided 65 with an extension p, engaging a suitable bearing in a sleeve p', fitting within the cylinder and secured to the extension i. Extending centrally through the cylinder is a shaft q, to which is secured the segmental piston r. This shaft 70 is journaled in bearings in the extension m at one end, and at the other end it engages a block s, journaled in the sleeve p', being held from longitudinal disengagement by the plates'. The block s has on it a stub-shaft t, to which is secured the rock-arm M, Fig. 1, connected by the connecting-rod M' with the eccentric M' 75 on the shaft B. Suitable means (which it is not necessary to describe) are provided for adjusting the length of the crank-arm M and for 80 adjusting the length of the connecting-rod M'. By this connection the segmental piston r is rocked to draw in the material from the hopper and to discharge it through the discharge-port. The cylinder is given a partial rotation, so as to register its discharge-port u with the port G' of the hopper or with the exit-ports by means of the rack-bar N, which 85 meshes with the gear k. The enlargement j is cut away on one side to allow this gear k 90 to project therethrough, so that the rack may engage therewith, as shown in Fig. 2. This rack is guided in a suitable guide N' on the side of the hopper, and is connected to the bar N'', which is provided with roller-wrists 95 O and O' at opposite sides of the cam P. The bar N'' has a slot P', which embraces the shaft B, so as to guide it in its movement. This cam is so constructed as to give the desired movement to the rack-bar N, and through the gear k to partially rotate the cylinder for the purpose previously described.

The parts being thus constructed their operation is as follows: The material being placed in the hopper G the cylinder L is first rocked, so that this port *u* connects the interior of the cylinder with the hopper. The segmental piston *r* is then moved from its lowermost position to its upper position and draws the material from the hopper into the cylinder. The cylinder is then rocked back to the position shown in Fig. 3, registering the port *u* with the discharge-ports through the nozzle, and the piston *r* is then rocked downward, forcing the material out. The table having suitable pans on it carried by the endless carrier is then fed downward and forward in position for another deposit.

This construction is exceedingly simple both in its construction and the number of parts employed. It can be readily cleaned, and all the ports and passages are large and clear, so that it will reduce the amount of friction, kneading, or churning in the operation of the device.

What I claim as my invention is—

1. The combination of a material-hopper having an exit throat or port, a cylinder journaled in said throat having a port, a discharge-passage below the throat, a stationary abutment in the cylinder, a rocking piston in the cylinder, and means for rocking the cylinder and piston for the purpose described.

2. The combination of a material-hopper having an apertured base, and an exit-throat above the aperture in the base, of a cylinder journaled in said throat having a port in its side adapted to be registered with the hopper or the aperture in the base, a stationary abut-

ment in the cylinder, a rocking segmental piston in the cylinder, and means for rocking the cylinder and piston, for the purpose described.

3. The combination of the material-hopper having a discharge-throat, a discharge-port below the throat, a cylinder journaled in said throat and having a port adapted to be registered with said hopper or the discharge-throat, an extension of the cylinder outside the hopper, a gear thereon, a rack and means for reciprocating the rack to rock the cylinder.

4. The combination of the material-hopper having a discharge-throat, a ported cylinder journaled therein, and extensions at the base of the hopper in which the ends of said cylinder rotate, the enlargement of one of said extensions having a cut-away portion, a gear on said cylinder within such enlargement, and a reciprocating rack-bar engaging said gear at the cut-away portion of the enlargement.

5. The combination of the material-hopper having a discharge-throat, a ported cylinder journaled therein, the end plate *l* having the inward extension *m* fitting within the cylinder at one end, the sleeve *i* in the other end of the cylinder, the shaft *q* journaled in the extensions, the segmental piston secured to the shaft, and the detachable abutment in the cylinder.

In testimony whereof I affix my signature in presence of two witnesses.

ALEXANDER W. COPLAND.
